BEVERAGE STIRRER

Edward C. Sterba, 4332 Howard, Western Springs, Ill.

Filed May 11, 1964, Ser. No. 79,899

Term of patent 14 years

(Cl. D44—29)

FIG. 2

FIG. 1

FIG. 4

FIG. 1 is a front elevational view of a beverage stirrer showing my new design;

FIG. 2 is a top plan view;

FIG. 3 is a bottom plan view; and

FIG. 4 is a side elevational view.

I claim:

The ornamental design for a beverage stirrer, as shown.
